FIG. 1.

INVENTOR =
By John E. Holmes
By Arthur F. Randall,
Atty

UNITED STATES PATENT OFFICE

2,462,321

RACK

John E. Holmes, Auburndale, Mass., assignor to
Clarence W. Carlson, Atlantic, Mass.

Application December 19, 1945, Serial No. 635,954

1 Claim. (Cl. 211—123)

1

This invention relates to racks for use in holding and displaying articles, particularly wearing apparel such as women's dresses and it has for its object to provide an adjustable rack of this description which will be of simple, inexpensive, attractive and efficient construction.

To this end I have provided an improved display rack of the character described which, in the preferred embodiment of the invention, may be constructed as set forth in the following description, it being understood that modifications of the invention not herein disclosed are intended to be included within the scope of the appended claims by which the several features of the invention are separately pointed out.

In the accompanying drawings:

Figure 1 is a front elevation, partly broken away, of a rack constructed in accordance with this invention.

Figure 2 is a section on line 2—2 of Fig. 1.

Figure 3 is a section on line 3—3 of Fig. 1 and on line 3—3 of Fig. 2.

Figure 4 is a section on line 4—4 of Fig. 1.

The illustrated embodiment of my invention comprises a rectangular wooden frame consisting of a base 10 on top of which are rigidly fastened the lower ends of a pair of relatively parallel spaced-apart vertical side members or standards 11, 11, whose upper ends are rigidly connected by a top cross-bar or lintel 12.

Each standard 11 includes, as a part thereof, an elongate longitudinally disposed apertured metal channel member 13 that is about three feet long and fixedly fastened by screws 14 to the inner side of its standard with its upper end abutting cross-bar 12. These two metal members 13 are preferably bars of channel iron each of which is disposed with its flanges fitted edge-wise against its standard so that its web 13a is spaced away from the standard as shown in Figs. 3 and 4.

The web 13a of each metal member 13 is provided with a longitudinal row or series of spaced-apart key hole slots 14a having their smaller ends disposed lowermost with each slot of one member disposed horizontally opposite one of the slots of the other member.

The key hole slots 14a are provided for the reception of studs 15 and 16 provided at the opposite ends of one or more, usually a plurality, of cross-bars 17 each of which comprises an intermediate chromium plated metal tube 18, a chromium plated cap 19 driven into position upon one end of said intermediate tube 17 and permanently fixed in position thereon by a screw 20

2

(Fig. 4), and a chromium plated cap 21 telescopically and loosely associated with the opposite end of tube 18.

The stud 16 of cap 19 is circular in cross-section and provided as an axially disposed integral extension of cap 19 (Fig. 4), while the stud 15 is also circular in cross-section and made as an axially disposed integral extension of the cap 21 (Fig. 3).

Within the end of tube 18 that is associated with cap 21 there is welded or otherwise permanently fixed an interiorly threaded bushing 22 (Fig. 3) that is occupied by an axially disposed threaded stem 23 that is an integral part of cap 21.

The shank portion of each stud 15 and 16 is of a diameter slightly less than the width of the lower relatively narrow portion of each slot 14a and each of said studs is provided at its free end with a radial flange 24 whose diameter is slightly less than the size of the partly-circular upper relatively larger end portion of the slot.

To prepare a cross-bar 17 for installation within the above described frame the cap 21 is screwed on to tube 18 until the distance between the extremities of studs 15 and 16 is less than the distance between the two metal members 13 whereupon one of the two studs is inserted within one of the slots 14a of one member 13 and permitted to drop to the bottom thereof after which the cap 21 is screwed outwardly relatively to tube 18 while maintaining the other stud in register with the upper end of the corresponding slot 14a of the other member 13. When the flanged end of said last-mentioned stud is entirely within its channel member 13 it is permitted to descend to the lower end of its slot after which cap 21 is screwed outwardly relatively to tube 18 until the two caps at the opposite ends of the latter are forcibly clamped against the two members 13. The cross-bar is thus rigidly fixed in position within the rectangular frame so that it cannot be displaced when garments are hung thereon or removed therefrom.

The described construction provides for bodily vertical adjustment of the cross-bars 17 relatively to the frame and also relatively to each other according to the size and type of the garments in order that the latter may be displayed to the best advantage.

The flanges 24 positively lock the studs within the slots 14a while said studs are within the lower parts of the slots and cannot be withdrawn except by adjustment of cap 21 while the cross-bar 55 that is to be removed is held near the limit of its

upward movement relatively to the pair of slots that are occupied by its studs. While inserting or removing one of the cross-bars the stud at one end thereof will first be inserted within a slot 14a of one channel and maintained at the bottom of said slot while the cap 21 is adjusted either to insert its stud into a slot of the proximate channel or to remove it therefrom and during this operation the flange 24 of the first-mentioned stud at the opposite end of the bar will prevent said stud from slipping out of its slot.

What I claim is:

As a new article of manufacture, a rack of the character described, comprising an upright rectangular frame including a pair of vertical spaced-apart uprights each of which has fixed upon its inner side an elongated vertically disposed metallic channel member whose flanges are seated edgewise against its upright and whose web is formed with a vertical series of spaced-apart stud-receiving key hole slots disposed with their narrower ends lowermost and with each slot horizontally opposite one of the slots of the other channel member; a longitudinally extensible and contractible article-supporting cross-bar including a tubular intermediate element having a cap member telescopically and rotatably fitted upon the exterior of one end thereof and a cap member telescopically and fixedly mounted upon the opposite end thereof, one of said cap members being provided upon its outer end with an axial flanged stud adapted to be removably fitted into a slot of one of said channel members and the other cap member being pro-

5
10
15

vided upon its outer end with an axial flanged stud adapted to be removably fitted into a slot of the other channel member, and said rotatable cap member being made interiorly with an axial threaded stem projecting into the proximate end of said tubular intermediate element and having threaded engagement therewith so that when rotated relatively thereto in one direction it is adjusted longitudinally thereof in one direction to fixedly clamp the opposite ends of the article-supporting cross-bar to the channel members and so that when rotated relatively thereto in the opposite direction it is adjusted longitudinally thereof in the opposite direction to free said article-supporting cross-bar for removal.

JOHN E. HOLMES.
